BURNER

Millard Cole Spencer, East Orange, N. J., assignor to Crocker-Wheeler Electric Manufacturing Company, Ampere, N. J., a corporation of New Jersey

Application April 26, 1935, Serial No. 18,328

3 Claims. (Cl. 158—28)

The object of this invention is to provide a simple, efficient, economical and durable burner and ignition means therefor which utilizes liquid fuels, particularly the heavier hydrocarbon oils, such as fuel oils and kerosene as for example, for the quiet operation of furnace burners and for internal combustion engines of such types as ordinarily run with the lighter hydrocarbon oils such as gasoline.

10 Further objects are to provide a burner which can be ignited and started by electrical means with a minimum use of electric current.

In the accompanying sheet of drawings which forms a part of this description,

15 Figure 1 is a vertical section through a vaporizer on the lines I—I of Figs. 2, 3, 4 and 5, with a burner and igniter which embodies this invention.

Fig. 2 is a cross section on the line II—II of Fig. 1, showing the valve through which fuel is admitted to the burner.

Fig. 3 is a cross section on the line III—III of Fig. 1, showing the electrical heater coil for radiating heat to the vaporizing plate in a burner.

25 Fig. 4 is a cross section on the line IV—IV of Fig. 1, showing the vaporizing plate.

Fig. 5 is a cross section on the line V—V of Fig. 1, through one of the retorts in the combustion chamber.

30 An enclosed combustion chamber 10 has a main vaporizer burner 11 in its lower end and in communication with its upper end a burner and igniter 12 which is electrically heated. The burner is provided with an air supply from a conduit 13, and a first portion of fuel from a fuel conduit 14, which is a source of fuel supply, through a needle valve 15 in the removable head of the burner. The fuel supply passes from the valve through a continuation of the fuel conduit

35 16 which is coaxial with the surrounding air conduit in the burner and is discharged from a nozzle 17 at the lower end. In this section of the conduit is a rod 18 with a helical groove similar to the groove of a twist drill. This retards the passage of the fuel so that it may be sufficiently heated before it is discharged at the nozzle. A cylinder of fireclay 19 surrounds the lower end of the fuel conduit and an electrical heater coil 20 surrounds the cylinder as a helix and is continued

40 as a spiral adjoining the lower end of the cylinder and the inner end of the spiral is welded to the nozzle and is grounded by the conduit. The other end of the coil is welded to a copper rod 21, the upper end of which is riveted to an insulated plate 22 which carries a binding post 23. This

together with a binding post 24 mounted on the cap of the burner serve for current supply to the electrical heater coil.

Closely adjacent to the spiral portion of the heater coil is a vaporizing plate 25 of fireclay forming with the coil a confined space into which this first portion of the fuel is discharged and vaporized. First, the current is turned on for about a minute so that the coil and the plate by radiation from the coil will both be brought at 10 least to a dull red heat and then the fuel is discharged and will be repelled from the hot surfaces and vaporized without deposit of hard carbon. The incoming air passes the helical part of the heater coil, mixes with the vapor coming from between the plate and the spiral part of the heater coil and is ignited from the convolution at the corner connecting the helical part with the spiral part and the flame is deflected past the edges of the plate and beyond the coil 15 so that the heat of the flame will not be added to the electrical heat and the coil overheated and burned. The flame passes down a central tube 26 through a first retort 27 and a second retort 28 and the flame and gases flow up through flues 25 between ribs 29 between the outside walls of these retorts and the wall of the combustion chamber and are discharged through an exhaust flue 30 at the top of the combustion chamber. Since there is no accumulation of residue in these 30 retorts it is not necessary to provide access thereto and the covers may be welded in place as shown.

When the walls of these retorts have been brought up to a dull red temperature or higher, a second portion of fuel is admitted through a needle valve 31 to a fuel conduit 32 to the first retort where it is vaporized and the vapor passes to a vapor supply conduit 33 the course of which is downward so that any oil condensing therein will readily drain out. From this conduit the vapor passes to an air supply conduit 34 leading to the combustion chamber. Air for the combustion of the vapor is supplied to the air supply conduit, and the mixed vapor and air is ignited from the flame directed downward from the burner and igniter 12. After the ignition, the electric current and the first portion of fuel in the burner and igniter are cut off, and a third portion of fuel is admitted through a needle valve 35 to a fuel conduit 36 to the second retort, and from this the vapor is drawn through a conduit 37 for any purpose for which it may be useful.

The air supply conduits receive air from a blower not shown.

I claim:—

- 5 1. A burner having a vaporizing plate, a fuel conduit with a nozzle positioned for discharging fuel onto the vaporizing plate, an air conduit surrounding and coaxial with the fuel conduit, a flame tube formed by an extension of the air conduit beyond the vaporizing plate, and an electrical heater coil having a set of its convolutions in the air conduit and a set of its convolutions positioned to heat the vaporizing plate by radiation and forming a vaporizing space between it and the plate and having an ignition 10 convolution between the two sets of convolutions at the discharge opening of the vaporizing space, the discharge opening of the air conduit and the entrance to the flame tube being also at the discharge opening of the vaporizing space, whereby 15 the air is caused to meet and mix with the vapor at the ignition coil and the ignited mixture conducted to the flame tube.
- 15 2. A burner having a vaporizing plate, a fuel conduit with a nozzle positioned for discharging fuel onto the vaporizing plate, an air conduit surrounding and coaxial with the fuel conduit, a flame tube formed by an extension of the air conduit beyond the vaporizing plate, and an electrical heater coil having a helical set of its convolutions in the air conduit surrounding the fuel conduit and positioned for heating the fuel 20 conduit and the air in the air conduit and a spiral set of its convolutions positioned to heat the vaporizing plate by radiation and forming a va- 25
- 20 30

porizing space between it and the plate and having an ignition convolution at the corner between the two sets of convolutions at the discharge opening of the vaporizing space, the discharge opening of the air conduit and the entrance to the flame tube being also at the discharge opening of the vaporizing space, whereby the air is caused to meet and mix with the vapor at the ignition coil and the ignited mixture conducted to the flame tube.

3. A burner having a vaporizing plate, a fuel conduit with a nozzle positioned for discharging fuel onto the vaporizing plate, a rod provided with a helical groove in the fuel conduit, an air conduit surrounding and coaxial with the fuel conduit, a flame tube formed by an extension of the air conduit beyond the vaporizing plate, and an electrical heater coil having a helical set of its convolutions in the air conduit surrounding the fuel conduit and positioned for heating the fuel conduit and the air in the air conduit and a spiral set of its convolutions positioned to heat the vaporizing plate by radiation and forming a vaporizing space between it and the plate and having an ignition convolution at the corner between the two sets of convolutions at the discharge opening of the vaporizing space, the discharge opening of the air conduit and the entrance to the flame tube being also at the discharge opening of the vaporizing space, whereby the air is caused to meet and mix with the vapor at the ignition coil and the ignited mixture conducted to the flame tube.

MILLARD COLE SPENCER.
